UNITED STATES PATENT OFFICE.

JOSEPH A. BERGER, OF CHICAGO, ILLINOIS, ASSIGNOR OF ONE-HALF TO
JOHN P. LARSON, OF SAME PLACE.

PNEUMATIC-TIRE FASTENING.

SPECIFICATION forming part of Letters Patent No. 655,183, dated August 7, 1900.

Application filed January 15, 1900. Serial No. 1,522. (No model.)

To all whom it may concern:

Be it known that I, JOSEPH A. BERGER, a citizen of the United States of America, and a resident of Chicago, in the county of Cook 5 and State of Illinois, have invented certain new and useful Improvements in Pneumatic-Tire Fastenings, of which the following is a specification.

My invention relates to means for attaching pneumatic-tire jackets to the rims of wheels by the use of studs engaging the jacket through eyelets therein; and my present application has particular reference to improved means for holding the studs upon the rim.

15 The main objects of my invention are, first, to provide inexpensive means for readily securing the studs to the rim, and, second, to provide for a slight longitudinal movement of the studs upon the rim for convenience in fastening the tire-jacket thereto. I accomplish these objects by the device shown in the accompanying drawings, in which—

Figure 1 is a cross-section of the rim and tire-jacket with fastening-strip secured together according to my invention. Fig. 2 is a longitudinal central section of same. Fig. 3 is a perspective view of part of the rim, showing studs secured thereto by means of a band or strap which is partly broken away.

30 The tire-jacket 1 has its lower edge 2 and its upper edge 3 each provided with a series of eyelets 4, located at uniform intervals around said edges. The studs 5 are provided with heads 6 of slightly-less diameter than said eyelets. A fastening strip or band 7 is secured to the rim 8 by means of the screws or tacks 9. Said band is provided with apertures 10, which are oblong in shape. The bases 11 of the studs are of greater diameter 35 than the width of said apertures. Said bases are seated loosely between the band 7 and the rim, thus giving the studs a slight movement in said apertures. This movement compensates for any slight difference that there 40 might be in the distances between the eyelets on the same or on different tire-jackets.

Both edges of the tire-jacket may be readily removed from the studs when the inner inflatable tube 12 is deflated. A protecting 45 flap 13 is secured to the tire-jacket toward its end 14. This passes over the heads of the

studs, as shown in Fig. 1, and protects the inner tube 12 against said studs.

The operation of the device is as follows: The band 7 will be tacked or screwed to the 55 rim supporting the studs 5, as shown in Fig. 3; with the heads 6 of said studs projecting above the rim. The edge 2 of the tire-jacket will now be secured to the rim by passing its eyelets over the studs. The inner tube 12 60 will then be inserted above the flap 13. The flap 13 and inner tube 12 will now be raised to admit the edge 3, when the eyelets in said edge will be passed over the heads of the studs. When the tube 12 is inflated, the edges of the 65 tire-jacket will be urged in opposite directions toward their respective sides. This serves to lock the edge 3 under said heads and upon the edge 2. If the tire becomes punctured at any part, the operator will deflate the inner tube, thus permitting him to 70 detach the edge 3 near the punctured part. The inner tube 12 will then be drawn out of the casing at the punctured part, when the puncture can be mended without disturbing 75 other parts of said tube and tire-jacket. Both edges of the tire-jacket may be readily removed from the studs when desired; but it will usually be sufficient to remove only the upper edge 3 at or near the punctured part. 80

The strip 7 is preferably made of metal; but it will be understood that a different material may be used and that the other details of my device may be altered without departing from the spirit of my invention. I therefore 85 do not confine myself to such details, except as hereinafter limited in the claims.

What I claim as my invention, and desire to secure by Letters Patent, is—

1. The combination of a wheel-rim; with a 90 metallic band having a series of apertures therein, and secured to said rim at points intermediate of said apertures; and a series of studs having heads of less diameter than the apertures and projecting through same, and 95 having bases of greater diameter than the width of said apertures, and resting loosely upon the rim; said studs being slidable longitudinally of said apertures; and a pneumatic-tire jacket having a series of eyelets in 100 each edge, adapted to pass over said heads, substantially as and for the purpose specified.

2. The combination of a wheel-rim with a continuous peripheral band having a series of apertures therein and secured to said rim at points intermediate of said apertures; a 5 series of studs having heads projecting through said apertures, and integral bases of greater diameter than the width of said apertures, resting between said band and rim, and unattached to said rim, except by said band;

and a pneumatic-tire jacket having a series 10 of eyelets in each edge, adapted to pass over said heads, substantially as specified.

Signed by me at Chicago, Illinois, this 11th day of January, 1900.

JOSEPH A. BERGER.
